Emile Louis Marin, *Attorneys.*

UNITED STATES PATENT OFFICE.

ALPHONSO COMSTOCK PRATT, OF DEEP RIVER, CONNECTICUT.

GROMET.

1,294,161.

Specification of Letters Patent. Patented Feb. 11, 1919.

Application filed December 10, 1917. Serial No. 206,568.

To all whom it may concern:

Be it known that I, ALPHONSO COMSTOCK PRATT, a citizen of the United States, residing at Deep River, in the county of Middlesex, State of Connecticut, have invented certain new and useful Improvements in Gromets; and I do hereby declare the following to be a full, clear, and exact description of the invention, such as will enable others skilled in the art to which it appertains to make and use the same.

This invention relates to gromets of the type consisting of a plurality of convolutions of a single length of wire, each convolution being wound spirally upon the others and the ends of the piece of wire being united together as by butt welding. Such gromets are widely used, more particularly in the manufacture of the shoes of automobile tires of the type known as "straight side" tires, wherein one of the gromets is incased within the rubber and fabric near the base of each of the straight sides.

The distinctive feature of the gromet constituting the present invention is that the spirals of the several convolutions of the gromet are not wound upon a core. The common practice heretofore followed in the manufacture of gromets has involved the provision of a complete convolution of straight wire serving as a core, followed by winding successive convolutions spirally upon this core. Usually the gromet has consisted of seven convolutions, one constituting the core and six others wound spirally upon this core, the spirals of the six outer convolutions lying side by side. The employment of such a straight convolution constituting a core has been essential by reason of the fact that the outer convolutions have been wound spirally by hand and a core was necessary to sustain the spirals during the winding operation.

The gromet of the present invention is preferably made by machinery, in accordance with a procedure which is distinctive in that the spirals are formed in the wire prior to applying the wire to the gromet, whereas the procedure heretofore followed in the manufacture of gromets by hand has involved spiraling the wire as an incident to its application to the gromet. By reason of this different procedure, it is possible to make a gromet which is hollow, that is, one

in which all of the several convolutions of spirally formed wire which constitute the gromet lie upon the surface of the gromet. Thus, a gromet of substantially circular cross-section can be made corresponding closely to those heretofore widely used in automobile tires but having six convolutions arranged symmetrically about the axis of a central space, instead of seven convolutions, six arranged symmetrically around a seventh one constituting a core.

Such a hollow gromet of circular cross-section made as above outlined may be subjected to pressure in any suitable manner to cause it to assume the cross-section of an equilateral triangle, contracting its cross-sectional size by taking up the central space. When the pressing devices are so applied that the apex of the triangle is at the outer side of the gromet and the inner side of the gromet is one of the flat sides of the triangle, a gromet is produced which is well adapted for use in automobile tires. When the hollow gromet of circular cross-section consists of six spirally wound convolutions of a single length of wire, the pressing of the gromet to the desired triangular cross-section causes the wire of three convolutions to lie side by side at the base of the triangle on the inner side of the gromet, one convolution to take position upon the apex of the triangle and the wire of the two remaining convolutions to lie between the one at the apex and the row of three at the base. At regular intervals around the circumference of the gromet, one convolution succeeds another at the apex of the triangle and at each other point around the surface of the gromet, but the triangular cross-sectional form of the gromet and the general arrangement of the six convolutions constituting this gromet of triangular form is maintained as above indicated.

An embodiment of the invention is illustrated in the drawing annexed hereto, wherein Figure 1 is a view of the gromet in elevation; Fig. 2 is a detail view of a section of the gromet on an enlarged scale; Fig. 3 is a cross-sectional view of the hollow gromet of circular form, that is, the gromet as originally made and before being subjected to pressure; and Fig. 4 is a similar cross-sectional view of the gromet after it has been subjected to pressure, the section of Fig. 4 being the line 3-3 of Fig. 2, so

as to indicate the location of the apex of the triangle with reference to the gromet as a whole.

Referring to these drawings, Fig. 1 shows 5 the gromet in elevation. It consists of a ring or hoop formed from a plurality of convolutions of wire, the wire of each of the several convolutions being wound spirally and the two ends of the wire being butt welded 10 together. Preferably, the gromet consists of six convolutions of the spirally formed wire, the six convolutions being arranged concentrically about the axis of a central space, as indicated in Fig. 3. The spiral 15 arrangement of the wire in each of the several convolutions is indicated in Fig. 2, from which it will appear that the several turns of the spirals of the several convolutions of wire forming the gromet lie side by side 20 around the entire circumference of the gromet.

After the manufacture of the gromet in the form indicated in Fig. 3 has been completed, the gromet is subjected to pressure to 25 contract its cross-sectional size by taking up the space at the center of the gromet and the pressing devices employed for this purpose are such as to give the gromet a triangular cross-sectional shape with the apex 30 of the triangle lying at the outer side of the gromet. This cross-sectional shape of the gromet is illustrated in Fig. 4, from which it appears that the central space within the gromet has been taken up and the several 35 convolutions of the wire from which the gromet is formed are caused to assume positions wherein three wires lie abreast on the inner side of the gromet, two wires lie side by side and against these three, and a single 40 wire lies at the apex of the triangle. The apex of the triangle is on the outer side of the gromet and at the inner side is one of the sides of the triangle. The spiral formation of all of the convolutions of the gromet 45 causes the six wires to come successively to the apex position and each of the other positions within the triangle indicated in Fig. 4, but notwithstanding this, the triangular cross-sectional shape of the gromet and the 50 arrangement of the wires in the manner indicated in Fig. 4, is substantially maintained throughout the entire circumference of the gromet. Any suitable mechanism may be employed for pressing the gromet from the 55 cross-sectional shape indicated in Fig. 3 to that indicated in Fig. 4. For instance, a pair of rolls may be employed, one having a V-shaped circumferential groove therein and the other having a flat periphery, means 60 being provided for pressing the rolls together with the requisite force. The use of such a mechanism may result in increasing

the circumferential length of the gromet; ordinarily this would not be objectionable as the gromet would be originally made of 65 a size which would allow for this increase. If desired, other forms of pressing mechanism may be employed, wherein the pressure is applied to all parts of the gromet simultaneously, thus avoiding any increase in the 70 circumferential length of the gromet.

It will be noted by reference to Figs. 3 and 4, that all of the six convolutions of spirally formed wire constituting the gromet as a whole lie upon the surface of the 75 gromet. There is no convolution constituting a central core upon which the other convolutions are wound, as has been characteristic of gromets heretofore made. This characteristic of the gromet shown in Fig. 80 3 permits of pressing the gromet to the form illustrated in Fig. 4, which is particularly favorable to use of the gromet in the manufacture of automobile tires. The manufacture of gromets in the form indicated with 85 all of the several convolutions lying upon the surface is made possible by giving the wire constituting the several convolutions its spiral formation and "killing" the metal of the wire so that it will hold its spiral formation, before applying the wire to the gromet, as distinguished from giving the wire its spiral formation incident to applying it to the gromet.

I claim:

1. A gromet comprising the combination of a plurality of convolutions each wound spirally, the gromet being formed from a continuous piece of wire having its ends secured together and having all of its convolutions lying upon the surface of the gromet; substantially as described. 95

2. A gromet comprising the combination of a plurality of convolutions, each wound spirally, the gromet being formed from a continuous piece of wire having its ends secured together and being of triangular cross-section throughout; substantially as described. 105

3. A gromet consisting of six convolutions of a continuous piece of wire having its ends secured together, each convolution consisting of a succession of spirals, and the gromet being substantially triangular in cross-section throughout and at each of a 110 multiplicity of points having three convolutions lying side by side on the inner side of the gromet, one convolution lying at the apex of the triangle on the outer side of the gromet and the two remaining convolutions 115 lying between them; substantially as described. 120

In testimony whereof I affix my signature.
ALPHONSO COMSTOCK PRATT.
